(57) **CLAIM**

The ornamental design for a tool parts container, as shown
and described.

DESCRIPTION

FIG. 1 is a perspective view of a tool parts container, showing
my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a perspective view thereof showing the container
mounted in a broken line housing; and,

FIG. 10 is a perspective view thereof showing the tool parts
container in condition of use with multiple broken line
containers and housing.

The broken lines depict portions of the tool parts container
that form no part of the claimed design, as well as environ-
mental structure and multiple containers that also form no
part of the claimed design.
